UNITED STATES PATENT OFFICE.

CLYDE VERKRUYSSE, OF ATKINSON, ILLINOIS.

SIDE-DRAFT-ELIMINATING DEVICE.

Application filed September 21, 1928. Serial No. 307,394.

This invention relates to a device or mechanism useful in the prevention of side draft or lateral sluing of vehicles when drawn by tractors or the like.

5 A more particular object of the invention is to provide means to offset the natural tendency of the rear or main frame of road maintainers to move laterally toward the gutter or off side of a road when connected 10 to and being drawn by a tractor or the like.

The present invention is especially adapted for use in connection with vehicles embodying a rear or main frame provided with a front steering truck having a forwardly 15 projecting draft pole or tongue, and the invention provides means for adjustably sustaining the draft pole or tongue at an angle to the longitudinal axis of the rear or main frame of the vehicle, so that when the vehicle is drawn forwardly by a tractor or the like connected to the draft pole or tongue, the latter is constantly subjected to a force 20 tending to shift the same parallel with the line of draft or the longitudinal axis of the main frame, thereby simultaneously subjecting the rear or main frame to a force tending to shift the same laterally toward the inner or near portion of the road, thereby 25 effectively offsetting or eliminating the side draft or the natural tendency of the main frame to shift laterally toward the gutter or off side of the road.

Still another object is to provide a side draft eliminating device of the above kind 30 which may be readily applied to vehicles already in use, and which is extremely simple in construction, economical to manufacture and install, and efficient in use.

Other objects will appear as the nature of 35 the invention is better understood, and the same consists in the novel form, combination and arrangement of parts hereinafter more fully described, shown in the accompanying drawings, and claimed.

40 In the drawings:

Figure 1 is a top plan view of a road maintainer equipped with a side draft eliminating device embodying the present invention.

Figure 2 is an enlarged fragmentary side 45 elevational view of the construction shown in Figure 1, looking toward the inner or near side of the main frame of the road maintainer and showing details of construction of the invention.

Figure 3 is a top plan view of the construction shown in Figure 2.

Figure 4 is a fragmentary vertical section taken on line 4-4 of Figure 2.

Figure 5 is a fragmentary horizontal section taken on line 5-5 of Figure 2; and 60

Figure 6 is a perspective view of one of the cable guides forming part of the present invention.

The invention is shown in connection with a road maintainer of the type disclosed in 65 the U. S. patent to B. R. Bonney, No. 1,357,685, dated November 2, 1920, when provided with a steering means of the type disclosed in the U. S. Patent to B. R. Bonney No. 1,451,757, dated April 17, 1923. The road 70 maintainer has a rear or main frame 11 supported at its front end by a steering truck 12 and provided at its rear end with supporting wheels 13. Scraper blades 14 are disposed transversely of the rear frame at an oblique 75 angle to the longitudinal axis of the latter, it being understood that the blades may be elevated or lowered by means of certain levers. The road maintainer also includes an under frame consisting of an angle bar or cross plate 80 6 and suitable hangers 7, the angle bar or cross plate 6 being disposed parallel with and in front of the blades 14 and being principally supported by the main frame 11.

It will be understood that the blades 14 are 85 for the purpose of engaging and scraping the surface of the road to provide and maintain a smooth surface for the latter, the maintainer being drawn forwardly by a tractor or the like for performing the road surfacing operation. In order that the movements of the 90

maintainer toward the near or off side of the road may be controlled practically independent of the forward movement of the tractor while connected with the latter, it has been 95 proposed to provide a draft pole or tongue 15 pivotally connected at its rear end with the front end of the frame 11 and with the bolster *a* of the steering truck 12, by means of a king pin 16, the draft pole or tongue 15 having an eye *b* at its forward end for connection 100 with the tractor or the like, and means being provided for swinging the steering truck 12 to any desired position relative to the draft pole or tongue 15 so as to change the direction 105

of movement of the truck and maintainer, while the draft pole or tongue 15 is connected to the tractor for drawing the maintainer forwardly. However, due to the pivotal connection between the main frame 11 and the steering truck 12, said main frame has been 110 left free to swing or slue laterally toward the

outer or off side of the road, thus resulting in objectionable side draft. Due to the oblique angle at which the blades 14 are set, and the slope of the side of the road, this side draft is 5 a natural tendency or result when the maintainer is drawn forwardly. It is thus apparent that the provision of steering means alone, while of some value in steering the maintainer independently of the tractor, does 10 not produce the desired result in a satisfactory manner, due to the fact that side draft is not eliminated.

In order to effectively eliminate the objectionable side draft mentioned above, I provide 15 means for connecting the draft pole or tongue 15 with the rear of the main frame 5 at the inner or near side of the maintainer so as to sustain the draft tongue or pole 15 at an angle to the line of draft or the longitudinal 20 axis of the main frame 11. Furthermore, in order that proper elimination of side draft may be effected under different or constantly changing road and operating conditions, the means of the present invention is preferably 25 adapted for adjustably sustaining the draft pole or tongue at an angle to the line of draft or at any one of several different angles relative to the longitudinal axis of the main frame 11. With such an arrangement, the objectionable side draft will not only be eliminated, but the action of the steering mechanism will 30 be rendered more efficient in controlling the direction of movement of the maintainer.

The maintainer has been shown as provided 35 with steering means such as is disclosed in the Bonney Patent No. 1,451,757 mentioned above, the same consisting of a yoke 19 mounted on the forward end of the reach bar 18 of truck 12 and disposed transversely of said reach bar beneath the draft tongue 15 intermediate the ends of the latter, and means for applying power to the reach bar 18 so as to cause it to swing transversely of the tongue 15. The means for applying power to the reach bar 18 is clearly described in the last mentioned Bonney patent and needs no more specific description herein, it being mentioned however, that the same includes the steering shaft 21 provided at its rear end with a hand wheel 22 and operatively connected at its forward end with the yoke 19, and with the draft pole or tongue 15.

The embodiment of the present invention which is illustrated in the accompanying drawing, embodies a vertical or upright winding drum 25 journaled at the inner or near side of the frame 11 near the rear end of the latter and having a cable 26 attached to and adapted to be wound thereon, the cable 26 being extended forwardly and provided upon its free end with suitable means such as a hook 27 engageable in the eye b of the tongue 15 for connecting the same to the forward end of said tongue. It will thus be seen that by 60 winding the cable or equivalent flexible mem-

ber 26 upon the drum 25 the tongue 15 may be adjusted to the desired angle to the line of draft or the longitudinal axis of the frame 11 and in a forwardly and inwardly extending position as shown in Figure 1. It will also be seen that if the drum 25 is restrained against rotation so as to prevent unwinding of the cable therefrom, the tongue 15 will be sustained at the angle to the line of draft, whereby, when the maintainer is drawn forwardly by a tractor or the like connected to the front end of the tongue 15, the tendency will be to swing the tongue 15 toward the outer or off side of the maintainer or toward a position parallel with the line of draft. 70 This tendency, in combination with the connection between the front end of the tongue 15 and the rear portion of the frame 11 at the inner or near side of the maintainer, will result in a force being applied to the rear end of the frame 11 tending to shift the same laterally toward the inner or near portion of the road, thereby offsetting the natural tendency of the frame 11 to sue or move laterally toward the outer or off side of the road by 75 reason of the inclination of the side of the road upon which the machine is operating and by reason of the oblique position of the blades 14. In this way the objectionable side draft is effectively prevented or eliminated, 80 and maintenance of the steering truck 12 and tongue 15 in any desired relation to the frame 11 is insured for most efficient steering and side draft preventing actions according to 85 road conditions, etc. At the same time, the truck 12 may be adjusted independently of the tongue 15 relative to the line of travel, thus increasing the efficiency of the steering operation effected by swinging the reach bar 18. It will be particularly noted that the 90 present invention greatly increases the effective range of the steering mechanism by reason of the fact that the maintainer may be drawn forward when the tongue 15 is disposed at a forward and inward angle. This permits swinging of the reach bar 18 a considerable distance toward the inner or near side of the maintainer, a condition which is not presented where the tongue 15 is allowed freedom of movement relative to the frame 11 and naturally assumes a position in line with the longitudinal axis of the maintainer. 95

In order that the movement of the tongue 15 to the right or left may be readily changed and will be under convenient control of an operator, I provide the upper end of the winding drum 25 with a worm gear 28 which meshes with a worm 29 secured upon the adjacent end of an operating shaft 30 which is provided at its opposite end with a hand wheel 31. The operating shaft 30 extends laterally or inwardly and rearwardly from the drum 25 to a point adjacent the rear operator's platform 5 of the road maintainer, thus locating the hand wheel 31 within con- 100 105 110 115 120 125 130

venient reach of the operator for operating the winding drum 25 to wind the cable 26 on or unwind the same from said drum.

The shaft of drum 25 is supported at its lower end in a bearing 32 provided on an angle bracket 33 fastened upon the inner end portion of the angle bar or cross plate 6, as clearly shown in Figures 2 and 5. The upper end of the shaft of drum 25 is journaled in a suitable block or casting 34 having bearings 35 for the adjacent end portion of the operating shaft 30, and between which bearings 35 the worm 29 is positioned so as to be held against axial displacement. The casting or block 35 is sustained in position and braced against lateral strains by means of suitable braces 36 attached thereto and extended outwardly and attached to the frame 11 as well as downwardly and attached to the angle bar 6. The braces 36 are assembled to the bearing block 34, and are so arranged as to be readily bolted to the frame 11 and angle bar 6 along with the angle bracket 33. In this way the device is adapted for ready attachment to or installation upon existing road maintainers so as to present a simple, durable and efficient mechanism.

Guides 37 and 38 are respectively attached to the forward and intermediate portions of the frame 11 at the inner or near side of the latter, and the cable 26 is extended through these guides so that it is sustained at a proper elevation to properly wind upon the drum 25 without winding below the lower end of the latter. These guides may be of any preferred or well known construction, but the rear guide 38 preferably consists of a hook-shaped piece of strap metal adapted to be bolted at one end to the frame 11 where one of the braces 36 is bolted to the latter in front of the winding drum 25. This rear guide is clearly shown in Figure 6.

In using the present side draft eliminating device, the operator turns the hand wheel 31 for rotating the drum 25 in the proper direction for winding the cable 26 on or unwinding the same from said drum and thereby adjusting the tongue 15 at the desired angle to the longitudinal axis of the frame 11, as the case may be. Due to the self-locking nature of the worm gearing at 28 and 29, the winding drum 25 will be maintained against accidental rotation so that the tongue 15 will be sustained in any position to which it is swung. The tractor may then travel at or near the middle of the roadway and be steered independently of the road maintainer, the draft being transmitted however by the cable 26 and associated parts to the rear end of the frame 11 so as to offset its natural tendency to draft sidewise toward the outer or off side of the road. By the use of the means presented herein, the utility of road maintaining machines has been greatly increased. However, while the embodiment of

the invention herein shown and described has given satisfactory results in actual practice, it is nevertheless to be understood that various changes in the form, combination and arrangement of parts such as will come fairly within the scope of the appended claims are contemplated and within the purview of the invention.

What I claim as new is:

1. The combination with the main frame 75 of a vehicle having a front steering truck, a draft tongue pivotally connected at its rear end to the steering truck and adapted to be coupled at its front end to a tractor or the like, and means for adjustably sustaining 80 said steering truck at an angle to said draft tongue, of means for adjustably sustaining said draft tongue at an angle to the longitudinal axis of said main frame.

2. The combination with the main frame 85 of a vehicle having a front steering truck, a draft tongue pivotally connected at its rear end to said steering truck, and means to steer said truck relative to the main frame and said draft tongue, of an extensible draft connection 90 between the forward end of said draft tongue and the rear inner side portion of said main frame.

3. The combination with a road maintainer having a main frame provided with a 95 front steering truck, a draft tongue pivotally connected at its rear end to said steering truck, and means to adjustably swing said steering truck relative to the main frame and said draft tongue, of a winding drum mounted 100 at the inner side of said main frame, a flexible member attached to and adapted to be wound upon said drum, means to connect said flexible member to the front end of said draft tongue, and means for turning said drum. 105

4. The combination with a road maintainer having a main frame provided with a front steering truck, a draft tongue pivotally connected at its rear end to said steering truck, means to adjustably swing said steering truck relative to the main frame and said draft tongue, of a winding drum mounted 110 at the inner side of said main frame, a flexible member attached to and adapted to be wound upon said drum, means to connect said flexible member to the front end of said draft tongue, means for turning said drum, a cross plate suspended from said main frame, a bracket secured on the inner end of said cross plate and having a bearing for the lower end of the shaft of said winding drum, a bearing block for the upper end of said drum shaft, and braces fixed to the bearing block and attached to the main frame to mount the drum in a vertical position. 115

5. The combination with a road maintainer having a main frame provided with a front steering truck, a draft tongue pivotally connected at its rear end to said steering truck, means to adjustably swing said steer- 120

ing truck relative to the main frame and said draft tongue, of a winding drum mounted at the inner side of said main frame, a flexible member attached to and adapted to be wound upon said drum, means to connect said flexible member to the front end of said draft tongue, means for turning said drum, a cross plate suspended from said main frame, a bracket secured on the inner end of said cross plate and having a bearing for the lower end of the shaft of said winding drum, a bearing block for the upper end of said drum shaft, braces fixed to the bearing block and attached to the main frame to mount the drum in a vertical position, the drum turning means including an operating shaft having an end journaled in said bearing block and provided with a worm, and a worm gear on the upper end of the drum shaft meshing with said worm.

6. The combination with a road maintainer having a main frame provided with a front steering truck, a draft tongue pivotally con-

nected at its rear end to said steering truck, means to adjustably swing said steering truck relative to the main frame and said draft tongue, of a winding drum mounted at the inner side of said main frame, a flexible member attached to and adapted to be wound upon said drum, means to connect said flexible member to the front end of said draft tongue, means for turning said drum, and guides for said flexible member mounted on the inner side of said main frame forwardly of said drum.

7. A side draft eliminating attachment for road maintainers and the like, comprising a winding drum provided with operating means, means to mount said drum in an upright position on and at the inner side of the road maintainer, and a cable attached to said drum and provided at its outer end with means to connect the same to the forward end of the draft tongue of said road maintainer.

In testimony whereof I affix my signature
CLYDE VERKUYSE.
